[57] CLAIM

The ornamental design for a globe for a lamp, as shown and described.

DESCRIPTION

FIG. 1 is a top plan view of a first embodiment of a globe for a lamp showing my new design;

FIG. 2 is a side elevational view of the globe shown in FIG. 1;

FIG. 3 is a bottom plan view of the globe shown in FIG. 1;

FIG. 4 is a top plan view of a second embodiment of a globe for a lamp showing my new design;

FIG. 5 is a side elevational view of the globe shown in FIG. 4;

FIG. 6 is a bottom plan view of the globe shown in FIG. 4;

FIG. 7 is a side elevational view of a third embodiment of a globe for a lamp showing my new design;

FIG. 8 is a top plan view of the globe shown in FIG. 7, which top plan view is the same as a bottom plan view thereof.

FIG. 1

FIG. 2
